UNITED STATES PATENT OFFICE

ART KRUEGER, OF CHICAGO, ILLINOIS, ASSIGNOR TO SANDEL MANUFACTURING CO., OF CHICAGO, ILLINOIS, A CORPORATION OF ILLINOIS

DESIGN FOR A TABLE LAMP OR SIMILAR ARTICLE

Application filed January 22, 1932. Serial No. 42,597. Term of patent 3½ years.

To all whom it may concern:

Be it known that I, ART KRUEGER, a citizen of the United States, and resident of Chicago, in the county of Cook and State of Illinois, have invented a new, original, and ornamental Design for a Table Lamp or Similar Article, of which the following is a specification, reference being had to the accompanying drawing, forming a part thereof.

The figure is a front elevational view of a table lamp or similar article, showing my new design.

The rear of the lamp (not shown) is the same as the front view illustrated in the figure.

I claim:

The ornamental design for a table lamp or similar article, as shown and described.

Signed at Chicago, in the county of Cook and State of Illinois, this 19th day of January, A. D. 1932.

ART KRUEGER.
